AUTOMOBILE WHEEL COVER

Charles Mashigan, Redford Township, Wayne County, Mich., assignor to Chrysler Corporation, Highland Park, Mich., a corporation of Delaware

Filed June 27, 1962, Ser. No. 70,710

Term of patent 7 years

(Cl. D14—30)

FIG. 1 is a front elevational view of an automobile wheel cover showing my new design;

FIG. 2 is a sectional view taken on the line 2—2 of FIG. 1;

FIG. 3 is a sectional view on an enlarged scale taken on the line 3—3 of FIG. 1; and

FIG. 4 is a fragmentary sectional view taken on an enlarged scale as indicated by the broken line 4 in FIG. 2.

The dominant features of my design reside in the full line portions of the drawing.

I claim:

The ornamental design for an automobile wheel cover, substantially as shown and described.
